T. IBARAKI.
CARPENTER'S MARKING LINE.
APPLICATION FILED JAN. 24, 1918.

Patented July 2, 1918.

UNITED STATES PATENT OFFICE.

TANAJIRO IBARAKI, OF SOUTH BETHLEHEM, PENNSYLVANIA.

CARPENTER'S MARKING-LINE.

1,271,470.

Specification of Letters Patent.

Patented July 2, 1918.

Application filed January 24, 1918. Serial No. 213,545.

To all whom it may concern:

Be it known that I, TANAJIRO IBARAKI, a subject of the Emperor of Japan, and a resident of South Bethlehem, in the county of Northampton and State of Pennsylvania, have invented a new and Improved Carpenter's Marking-Line, of which the following is a full, clear, and exact description.

This invention relates to a marking line adapted to be used by artificers, and it deals more particularly with that type of device which embodies a reel within a housing, and a coloring means associated with the reel so that as the line is drawn off the reel coloring matter will be deposited on the line so that it can be transferred to the work to be marked in the usual manner.

The invention has for its general objects to improve the construction and operation of devices of this character so as to be reliable and efficient in use, comparatively simple and inexpensive to manufacture, and so designed that the line will be effectively charged with coloring matter automatically during the drawing out of the line from the case or housing.

A more specific object of the invention is the provision of a case or housing having novel means for supporting and guiding the line, and simple, novel and effective means for applying a coloring matter to the line.

Still another object of the invention is the provision of a coloring means for applying coloring matter to the line, such means embodying a pad over which the line travels, and a wad pressed against the pad and line by a yielding follower carried by the lid of the casing, while in the body of the casing is held the pad and wad.

With such objects in view, and others which will appear as the description proceeds, the invention comprises various novel features of construction and arrangement of parts which will be set forth with particularity in the following description and claims appended hereto.

In the accompanying drawing, which illustrates one embodiment of the invention and wherein similar characters of reference indicate corresponding parts in all the views,

Figure 1 is a perspective view of the implement with the lid or cover partially raised;

Fig. 2 is a longitudinal vertical section; and

Fig. 3 is a vertical transverse section taken near the reel.

Referring to the drawing, A designates the casing or housing, B the lid therefor, C the marking line, D the reel, and E the coloring device for the line. The casing A is a narrow elongated box open at the top and the cover is connected at one end to the casing by a hinge 1, and a latch 2 and catch 3 on the cover and casing respectively at the opposite end serve to hold the cover closed.

The reel D is carried by an axle 4 which is journaled in the side walls of the casing and on one end of the axle at a point outside the casing is a foldable operating crank 5 whereby the reel D can be operated. The reel is arranged in the front end of the casing at the front side of a vertical partition 6. Set in the compartment 7 at the rear of the partition is a frame for holding the coloring device E and for holding the means to guide the line. This frame comprises a bottom plate 8, side plates 9 and transverse walls 10, all of which cooperate to form a well or chamber for holding the marking means E. In the chambers formed in the ends of this frame are guide pulleys 11 and 12 over which the line C travels. The walls 10 have guide openings 13 arranged tangentially to the bottoms of the pulleys 12, so that the line can pass through the coloring device E.

The coloring device E comprises a pad 14 set in the bottom of the chamber 15, and in direct contact with the top of the pad runs the line C. Over the pad 14 is a mass of cotton or other fibrous material forming a compression pad or wad 16, the bottom region of which may have coloring matter so as to assist in depositing coloring matter on the line. The presser pad 16 is pressed downwardly by a follower in the form of a plate 17 which is carried by the cover B and enters the top of the chamber 15. The follower is attached to the cover by springs 18. When the cover is raised the follower moves out of the chamber 15 so that the presser pad can be removed for applying coloring matter to the lower pad 14 and to the bottom region of the presser pad.

The free end of the line C is provided with a peg 22 formed with a handle 23, the line

being passed through an eye 24 in the peg and anchored at 25 on the handle 23. The peg is entered in the outlet aperture 26 of the casing when the line is fully wound up.

5 In using the device the peg 22 is set up in the work in the proper position and then the user moves away from the peg with the implement in his hands, and during this time the line is paid out, and when the desired point is reached the line is held taut in relation to the work and then drawn away and snapped against the work to mark a line thereon.

10 From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be 15 made when desired as fall within the scope of the appended claims.

20 Having thus described my invention I claim as new and desire to secure by Letters Patent:

25 1. A marking implement of the class described comprising a casing, a reel mounted in the casing, a frame in the casing and including a chamber having apertures, a line on the reel and passing through the chamber by the way of the said apertures, guiding means on the frame for the line, coloring means in the chamber, a cover for the casing, and means mounted on the cover for applying pressure to the coloring means.

30 2. A marking implement of the class de-

scribed comprising a casing, a reel mounted therein, a chamber in the casing, coloring means in the chamber, a line attached to the reel and extending through the chamber, guide pulleys mounted at opposite sides of the chamber for the line, and a pressure device acting on the coloring means to compress the same against the line. 45

3. A marking implement of the class described comprising a body, a cover hingedly connected with the body, a reel in the body, a marking line connected with the reel, a chamber in the body having apertures in its opposite walls through which the line passes, guiding means outside the chamber and adjacent the apertured walls for guiding the said line, a pad in the bottom of the chamber and over which the line has a rubbing contact, a body of fibrous material disposed in the chamber over the line and in contact with the pad, and a spring-pressed follower carried by the cover and arranged to enter the chamber for applying pressure to the fibrous material. 55

4. A marking implement of the class described comprising a box-like body, a reel therein, a marking line on the reel, a frame mounted in the body and formed with a chamber having apertures in its opposite walls, guide pulleys on the frame at opposite sides of the chamber and arranged in coöperative relation with the apertures for guiding the line into and out of the chamber, a pad in the chamber for applying coloring matter to the line, a mass of fibrous material over the pad and line, a cover for the body, and a yielding element carried by the cover for compressing the said fibrous material into engagement with the line. 70 75

TANAJIRO IBARAKI.

Correction in Letters Patent No. 1,271,470.

Affidavit having been filed showing that the first name of the patentee in Letters Patent No. 1,271,470, granted July 2, 1918, for an improvement in "Carpenters' Marking-Lines," should have been written and printed as *Tanajiro Ibaraki*, instead of "Tanajiro Ibaraki," it is hereby certified that the proper correction has been made in the files and records pertaining to the case in the Patent Office and should be read in said Letters Patent that the same may conform thereto.

Signed and sealed this 17th day of September, A. D., 1918.

[SEAL.]

F. W. H. CLAY,

Acting Commissioner of Patents.

Cl. 33--87.
